Primary Examiner — Darcey E Gottschalk*Assistant Examiner* — Vanessa M. Pursley(74) *Attorney, Agent, or Firm* — Womble Bond Dickinson (US) LLP(57) **CLAIM**

The ornamental design for a carton, as shown and described.

DESCRIPTION

FIG. 1 is a perspective view of a carton showing my new design.

FIG. 2 is a front elevation view of the carton of FIG. 1.

FIG. 3 is a rear elevation view of the carton of FIG. 1.

FIG. 4 is a left elevation view of the carton of FIG. 1, the right elevation view is a mirror image.

FIG. 5 is a top plan view of the carton of FIG. 1.

FIG. 6 is a bottom plan view of the carton of FIG. 1.

FIG. 7 is a plan view of the carton of FIG. 1 shown in an unfolded configuration.

FIG. 8 is a perspective view of an alternative configuration of the carton of FIG. 1; and,

FIG. 9 is another perspective view of the alternative configuration of the carton as shown in FIG. 8.

In the drawings, the broken lines depict portions of the carton that form no part of the claim.
